(57) **CLAIM**

The ornamental design for a baby carrier, as shown and described.

DESCRIPTION

FIG. 1 is a front elevational view of a baby carrier showing my new design in an exploded condition;

FIG. 2 is a front elevational view thereof in an assembled condition;

FIG. 3 is a front elevational view of the bib portion thereof, shown separately for clarity of disclosure;

FIG. 4 is a side perspective view thereof shown in use; and, FIG. 5 is a rear perspective view thereof shown in use.

The structural elements depicted by broken lines in the figures have been shown for the purpose of illustrating portions of the baby carrier that form no part of the claimed design.

The partial depiction of the person's torso with broken lines in FIGS. 4 and 5 has been shown to illustrate environment that forms no part of the claimed design.

The inside surfaces of the baby carrier, not shown, form no part of the claimed design.
